UNITED STATES PATENT OFFICE.

CLARENCE L. BARNHART, OF SOUTH BROOKLYN, NEW YORK.

STRIKING MACHINE.

Application filed April 1, 1922. Serial No. 548,718.

To all whom it may concern:

Be it known that I, CLARENCE L. BARNHART, a citizen of the United States, residing at South Brooklyn, in the county of and 5 State of New York, have invented certain new and useful Improvements in Striking Machines, of which the following is a specification.

This invention relates to improvements in 10 striking machines such as are employed in places of amusement and in which a blow is to be struck by a sledge upon a member which upon receiving the force of the blow will set in motion means to indicate, relatively, the degree of force with which the 15 blow was struck.

Ordinarily machines of the class above referred to require the presence of an attendant who collects the fees charged for the use 20 of the machine and in general keeps the same in order. However, in the absence of the attendant there is nothing to prevent surreptitious use of the machine with the result that the same is subjected to additional 25 wear and tear if indeed is not damaged. Furthermore the wages paid the attendant constitute a considerable item of expense and detract from the profits. It is therefore one of the primary objects of the present invention to provide a striking machine in 30 which coin controlled means is provided for normally rendering the machine incapable of use but which, upon depositing a coin in a place provided for that purpose, may be manipulated so as to permit of the use of the 35 machine, the restraining means being again immediately rendered active to prevent further use of the machine after a single blow has been struck upon the anvil member. In 40 this manner and by this means the presence of an attendant at the machine is rendered unnecessary and this portion of the expense is eliminated.

In most coin controlled machines a coin 45 of a specified denomination must be deposited in order to operate the machine or there must be deposited in the machine a token of a definite size or shape. If tokens are to be made use of then a cashier must be employed to sell the same, and if coins are to be used it is customary to employ a cashier to make change. If this is not done it will frequently happen that one who would use the machine is not provided with a coin of 50 the proper denomination, and the contemplated transaction will not take place.

Therefore it is another important object of the invention to so construct the coin controlled mechanism thereof that the same may be actuated by the deposit of a coin of 55 any one of several denominations. Thus the machine may be adapted to be actuated upon the deposit of a dime, a nickel, or a penny, for example, and as the machine is not of the vending type and no merchandise 60 is dispensed it is not of material consequence if the majority of coins deposited are of the smaller denomination and in fact the gross income from the machine will probably be greater than if it were adapted 65 to be rendered operable only upon the deposit of a coin of a specified denomination, as greater numbers will no doubt make use of it, and on the other hand one having coins only of a higher denomination will probably 70 deposit them rather than be put to the trouble of obtaining change.

It is the custom to employ in connection with the ordinary striking machine a sledge which is left lying about and may be made 75 use of by anyone in the absence of an attendant, but the present invention contemplates, as a further object, the provision in connection with such a sledge of means whereby its use may be prevented until such 80 time as a coin or token is deposited in the machine.

Also in the ordinary striking machine the anvil member is responsive to every blow struck upon it by the sledge and in responding to the force of the blow will actuate the means which registers the degree of such force. It is a further object of the present invention however to provide means whereby the anvil member will normally be maintained in such position that blows struck upon it will have no effect, the member being freed from restraint however automatically upon deposit of a proper coin in the machine and manipulation of the coin controlled mechanism. Therefore in the present structure, should one after having deposited a coin and once struck a blow upon the anvil member, attempt to make further free use 90 of the machine by striking subsequent blows, the anvil member will be restrained in a position such that it will not thereafter be responsive to blows except after proper manipulation of the coin controlled mechanism. 95

In connection with the sledge of the machine the present invention contemplates the provision of a flexible connection attached at one end thereto and extending into the casing of the machine and normally wound up to leave free only a relatively short portion of its length, the winding means being tensioned upon drawing out the said flexible connection to expose a sufficient length thereof to permit of use of the sledge, and it is a further object of the invention to provide means whereby the winding means may be rendered inactive to wind up said connection after it has been drawn out as stated and until such time as a blow has been struck upon the anvil member. By the provision of this means the sledge may be employed without imposing any restraint on the user so long as proper use is made of the machine.

In the ordinary striking machine an indicator member is impelled in an upward direction when the anvil member is struck a blow, and rising to a greater or less height depending upon the force of the blow, registers the degree of force exerted upon a scale arranged in proximity to the path of its movement, but the indicator member falls immediately after the impelling force has been exhausted, and the user of the machine is frequently unable to read the indicated force. The present invention therefore contemplates the provision of means for temporarily holding the indicating means in registering position so that after a blow has been struck upon the anvil member the degree of force will be registered and the parts will be maintained in registering position for a suitable period of time to enable the reading to be taken.

Another object of the invention is to provide means for giving an audible signal when one or more predetermined degrees of force are registered by the machine.

Another object of the invention is to provide novel indicating or registering mechanism capable of being more compactly arranged and housed than mechanisms of that type referred to above in which the indicator member is impelled vertically along a perpendicular wire or rod extending for a considerable height above the ground, and in this manner the machine embodying the present invention is adapted for indoor as well as outdoor use.

In the accompanying drawings:

Figure 1 is a perspective view of the striking machine embodying the invention;

Figure 2 is a rear elevation thereof, the door for closing the back of the casing being shown open;

Figure 3 is a vertical front to rear sectional view taken substantially on the line 3-3 of Figure 2 looking in the direction indicated by the arrows;

Figure 4 is a vertical sectional view substantially on the line 4-4 of Figure 2, and in detail, looking in the direction indicated by the arrows;

Figure 5 is a horizontal sectional view on the line 5-5 of Figure 4;

Figure 6 is a sectional view taken substantially on the line 6-6 of Figure 3 looking in the direction indicated by the arrows;

Figure 7 is a horizontal sectional view on the line 7-7 of Figure 6 looking in a downward direction;

Figure 8 is a detail horizontal sectional view through a portion of the locking mechanism; and

Figure 9 is a horizontal sectional view substantially on the line 9-9 of Figure 8.

The machine embodying the invention includes a casing which houses the greater portion of the mechanism and is indicated in general by the numeral 1 and this casing includes a front wall 2, side walls 3, a top 4, a base 5 which is provided with a forward extension 6 projecting beyond the plane of the front wall 2, and horizontal partition walls 7 and 8. A door 9 closes the back of the casing but may be swung to open position as shown in Figure 2 to permit of access to the mechanism housed within the casing. The casing may be constructed in various ways and designed and ornamented as desired, and of course its dimensions may be varied as occasion requires.

The anvil of the machine comprises a block 10 which may be of wood or metal and which is fixed in upright position upon the extension 6 of the base 5 and extends forwardly from the mid-portion of the front wall 2 of the casing. The upper surface of this block has a substantially horizontally disposed forward portion 11 and a downwardly inclined rear portion 12, and the front wall 2 of the casing is provided at the rear or lower end of the portion 12 with an opening indicated by the numeral 13. The anvil member heretofore referred to is indicated by the numeral 14 and comprises a beam 15 which is fulcrumed in any suitable manner as for example by an ordinary hinge 16, upon the upper surface of the block 10 at the juncture of the surface portions 11 and 12. There is preferably provided upon the upper side of the beam 15 at its forward end a buffer 17 which may be of rubber, leather, or other cushioning material upon which the blow is to be struck and which will protect the beam from injury. The portion of the beam 15 rearwardly of the fulcrum 16 is of greater length than the portion in advance of said fulcrum and therefore possesses greater mass and as a consequence the beam is normally overbalanced to assume substantially the dotted line position shown in Figure 3 of

the drawings, its forward end portion being in this position of the beam somewhat elevated above the surface portion 11 of the block 10. The anvil member when in this position is responsive to blows struck upon the buffer 17 by the sledge to be presently described, and if desired a buffer member 18 may be arranged upon the under side of the beam 15 at the forward end thereof for contact with the surface portion 11 and so as to prevent battering and injury of the beam and block through direct impact.

Passing now to a consideration of the indicating and registering mechanism, it will be observed that the same comprises a shaft 19 journaled at its lower end in a step bearing 20 upon the upper side of the partition wall 8 and at its upper end journaled through an opening 21 in the partition wall 7. A beveled gear 22 is fixed upon the upper end of the shaft and meshes with a similar gear 23 upon the rear end of a pointer shaft 24 mounted in a bearing 25 upon the said wall 7, this shaft projecting at its forward end through the front wall 2 of the casing and having fixed upon its said end a pointer hand 26 for cooperation with an annular dial or scale 27 upon the face of the wall 2 and concentric to the shaft 24. The numeral 28 indicates a cam member which is fixed upon the lower portion of the shaft 19 and which is provided with a volute portion 29. The portion 29 is arranged substantially in the path of movement of a rider 30 comprising a preferably cylindrical block 31 of wood, rubber, leather, or any other material and which, if not of metal, is preferably provided with a tubular bushing 32 extending axially therethrough and preferably flanged as at 33 over the upper end of the block and slidably fitting a guide rod 34 mounted vertically between cross pieces 35 within the casing 1. The rear end of the beam 15 comprising the anvil member 14 is slotted as at 36 to provide spaced portions 37 which extend at opposite sides of the lower end portion of the rod 34 and upon the upper sides of which the rider comprising the block 31 normally rests by gravity. It will now be evident, and particularly by reference to Figures 2 and 3 of the drawings, that when the rider 30 is in normal lowered position resting upon the rear end of the beam 15, and the beam is in the dotted line position shown in Figure 3, a blow struck upon the buffer 17 will sharply tilt the beam upon its fulcrum and cause the rider 30 to be impelled in an upward direction along the guide rod 34. As the rider moves upwardly it will ride against the volute portion 29 of the cam 28 and because of the contour of this portion, will rotate the cam and impart corresponding rotary motion to the shaft 19, this motion being in turn im-

parted to the shaft 24 and to the indicator hand 26 to move this hand over the surface of the dial 27 and thus register the degree of force with which the blow was struck upon the anvil member.

Means, to be presently described, is provided for temporarily holding the shaft 19 against backward rotation after it has been rotated through the action of the rider 30 against the cam 28 so that the hand 26 will remain at the extreme position to which it is rotated and until a reading of the indicator can be taken, and means is also preferably provided for giving an audible signal when one or more degrees of force are registered, the illustrated embodiment of the invention embracing two gongs 38 and 39 which are mounted upon the inner side of the front wall 2 of the casing and are adapted to give off readily distinguishable sounds or tones when struck. In connection with each of the gongs 38 and 39 there is provided a clapper 40 pivoted as at 41 and having a hammer 42 near its free end for impact with the peripheral portion of the respective gong. In connection with the clapper or striker 40 there is provided a trip 43 pivotally mounted as at 44 and yieldably held in one direction by a spring 45, the clapper or striker 40 being urged in a corresponding direction and toward the respective gong by a spring 46 connected thereto. A dog 47 is mounted upon the trip 43 and, when the trip is swung against the tension of the spring 45, is adapted to ride against a lug 48 upon the clapper 40 to first swing the clapper away from the respective gong and against the tension of its spring 46 and then ride past the said lug and disengage from the same to release the clapper for actuation by its said spring and cause it to strike the gong. Flexible cables or similar connections 49 are connected each at one end to a respective one of the trips 43 and at the other end to the shaft 24 and it will now be evident that when the shaft 24 is rotated, the connections 49 will be wound thereon and the trips 43 will be actuated to in turn actuate the clappers 40. In practice the connections 49 will be attached to the shaft 24 at such relatively located points that the trip 43 for the clapper of one of the gongs will be actuated when the shaft has been rotated through a predetermined angular distance, and subsequently if the shaft is rotated through a further predetermined angular distance, the trip for the clapper of the other gong will be actuated. Thus by providing two of the gongs and selecting ones which will give off different tones when sounded, readily distinguishable audible signals are given when the force delivered by the sledge striking the anvil member is of a predetermined degree or degrees.

In connection with the anvil member 14

there is provided a coin controlled detent indicated in general by the numeral 50 and designed to hold the said anvil member in such position that it will not respond to a blow struck thereon, the detent member being adapted for actuation however subsequent to deposit in the machine of a coin, to release the said anvil member and permit use of the machine. The detent member 50 comprises a bar 51 which is fulcrumed as at 52 upon the rear side of the front wall 2 of the casing. This bar is provided near its lower end with a shoulder 53 designed to engage beneath one side of the beam 15 comprising the anvil member, at a point adjacent the rear end of said beam. When the detent bar is in active position, it will support the rear end of the beam 15 in elevated position, and the buffer 17 at the forward end of said beam 15 will rest upon the surface 11 of the block 10. With the beam 15 thus held, it will not respond to a blow struck upon the buffer 17 and consequently no wear and tear will be imposed upon the operating parts of the machine if the sledge is mischievously or maliciously used or if one should attempt to use the machine without depositing a coin therein. Also the detent serves as a means for automatically locking the beam 15 in non-responsive position immediately after it has been struck a blow with the sledge and subsequent to the deposit of a coin in the machine.

The detent bar 51 is provided at its upper end with a coin pocket indicated in general by the numeral 54 and in providing this pocket one side of the detent bar is recessed as indicated by the numeral 55, and this portion of the bar constitutes one side wall of the pocket. The other side wall of the pocket is indicated by the numeral 56 and comprises an arm 57 pivoted at its lower end as at 58 upon the detent bar 51. Metal plates 59 are secured to the front and rear sides of the arm 57 and constitute the front and back walls of the coin pocket and extend in overlapping relation to the recessed upper end of the said bar 51. The arm 57 is also recessed as at 60 in its side which is presented toward the recessed side of the said bar 51. A spring 61 is connected at one end to the arm 57 and at its other end to the rear side of the front wall 2 of the casing and exerts a pull on the said arm 57 and consequently upon the upper end of the detent bar 51. A hand knob or handle 62 is secured to the front one of the plates 59 and extends through a transverse slot 63 formed in the casing wall 2, and the movement of the arm 57 and detent bar 51 under the influence of the spring 61 is limited by the engagement of the handle 62 in one end of the slot 63 as will best be understood by reference to Figure 7. It will now be evi-

dent that through the tension of the spring 61 the detent bar 51 is normally held in position rocked upon its fulcrum 52 to coact with the beam 15 to prevent response of this beam to the force of a blow delivered thereto. The numeral 64 indicates a coin chute which is formed integral with the rear one of the plates 59 or secured thereto in any suitable manner and which projects at its upper end into the space defined by the recesses 55 and 60. Below the said plate 59, the chute 64 is extended downwardly and preferably at an angle laterally with its lower end positioned above a coin receptacle 65 arranged within the casing 1. The space defined by the walls 59 and the opposing sides of the arm 57 and upper end portion of the detent bar 51 constitutes a coin receiving throat indicated by the numeral 66. This throat is gradually decreased in width from its upper to its lower end due to the angular disposition of the arm 57 with relation to the upper portion of the detent bar 51 and as will be evident by reference to Figure 6 of the drawings coins of several different diameters may be received within the throat and will lodge therein, substantially wedging between the side walls of the throat. For example the parts may be so proportioned as to adapt the throat to receive a dime, a penny, or a nickel as indicated in full and dotted lines in the said figure, and regardless of the denomination of the coin, it will temporarily constitute a means for preventing swinging movement of the arm 57 in the direction of and with relation to the upper portion of the detent bar 51. The front wall of the casing is formed, immediately above the throat 66 of the coin pocket in the normal position of the pocket, with a coin slot 67.

At this point it will be evident that if no coin has been deposited in the machine any attempt made to actuate the detent bar 51 to release the anvil member 14, by laterally shifting the handle 62, will serve only to swing the arm 57 about its pivot in the direction of the upper end portion of the detent bar but without imparting any movement to said bar. However if a coin has been deposited through the slot 67 and has lodged in the coin throat 66, it will form a wedge between the upper end of the detent bar 51 and the arm 57 and therefore when the handle 62 is shifted laterally in the slot 63, the upper end of the detent bar will be moved coincidently with the arm 57 thereby swinging its lower end to the dotted line position shown in Figure 2 and clearing the rear end of the beam 15 and permitting this end of the said beam to lower. After the handle 62 has been shifted in the manner stated it is released and upon release thereof the spring 61 will first act to swing the arm 57 away from the upper end of the

detent bar 51 thus widening the throat 66 and permitting the deposited coin to enter the upper end of the chute 64 from which it passes into the coin receptacle 65. When 5 the rear end of the beam 15 drops to lowered position, it constitutes an abutment for the shouldered lower end of the detent bar 51 and this bar will therefore be retained in the dotted line position in Figure 2 so long 10 as the beam 15 remains in the position stated. The widening of the throat 66 to discharge the coin as above pointed out, is provided for because of the detent bar being held stationary while the spring is exerting a pull 15 upon the arm 57 to swing it about its pivot. If now a blow is struck upon the forward end of the anvil beam 15, the rider 30 will be impelled in an upward direction and the indicator means will be actuated as previously 20 explained. At the same time the rear end of the beam 15 will ride upwardly along the adjacent side of the lower end portion of the detent bar 51 until it passes the shoulder 53 whereupon the said bar will be moved 25 through the medium of the spring 61 and will again engage and lock the said anvil beam.

If it were not for the provision of means to be now described, the indicator hand 26 30 would return to normal or zero position immediately after reaching the limit of its angular movement in accordance with the force of the blow struck upon the anvil member. This means is preferably in the nature 35 of a friction clutch for temporarily restraining backward rotation of the shaft 19 and this clutch comprises a pair of gripping members 68 and 69. The member 69 is preferably fixedly secured at one end as at 40 70 to the rear side of the front wall 2 of the casing or at any other conveniently located fixed point, and the members are connected at their meeting ends by a hinge joint 71 located relatively close to the said shaft 19, the members 68 and 69 straddling the shaft adjacent the connection 71. The free 45 end of the member 68 projects into a socket 72 formed in the rear plate 59 and arm 57, and it will be evident and particularly by 50 reference to Figure 7 that when the handle member 62 is shifted laterally in the slot 63 to actuate the detent member after a coin has been deposited in the coin throat 66, the member 68 will be swung in a direction away from the member 69 thus 55 releasing the shaft 19 for return rotative movement to normal position. Immediately after a blow has been struck upon the anvil member, however, and the shaft 19 is rotated through rotation of the cam 28, the 60 detent member in its return to normal position under the influence of the spring 61 will swing the member 68 toward the member 69 thus bringing the opposing sides of 65 these members into binding engagement

with the shaft 19. Therefore substantially at the moment the pointer hand reaches the limit of its movement in accordance with the degree of force imposed by the blow struck upon the anvil member, the shaft 19 70 will be clutched and retained in the position which it assumes at that moment and therefore the indicator hand will remain in the stated position until the detent 50 is substantially actuated. 75

The sledge which is employed is indicated in general by the numeral 73 and is of the usual form except that it is provided at the end of its handle with means 74 for the connection of one end of a cable, rope, chain, or the like indicated by the numeral 75. This flexible connection 75 is led through an opening 76 in the front wall 2 of the casing 1 and is wound about a winding wheel 77 rotatably mounted upon a stub shaft 78 fixed upon one side wall 3 of the said casing, the wheel having a grooved peripheral portion 79 to accommodate the flexible connection 75 and being further provided with an auxiliary drum portion 80 about which is wound a cable or other similar flexible element 81 one end of which is connected to the drum 80 and the other end to a coil spring 82 fixedly supported as at 83 upon the said side wall of the casing. The arrangement of the drum and the flexible elements 75 and 81 is such that when the element 75 is unwound from the wheel 77 by pulling it through the opening 76, the drum 80 will wind up the flexible element 81 against the tension of the spring 82. Also under conditions to be presently explained, when the winding wheel 77 is freed for rotation, the force exerted by the spring 82, in unwinding from the drum 80 the flexible element 81, will effect rotation of the said winding wheel to wind up the flexible element 75 and take up all but a short portion of the length thereof substantially as illustrated in Figure 1. As it would be undesirable to have the connection 75 tensioned while the sledge was being employed, means is provided for restraining backward rotation of the winding wheel 77 under the influence of the spring 82 after the said connection 75 has been unwound from the portion 79 of the wheel. Also means is provided for restraining the wheel 77 from rotation to permit of withdrawal and unwinding of the connection 75 until after a coin has been deposited in the machine and the detent 50 has been actuated. For these purposes a pawl 84 is provided and comprises a plate 85 having an opening 86 between its ends loosely receiving the shaft 78 whereby the pawl plate may have free rocking movement upon said shaft as a fulcrum. A coil spring 87 is arranged upon the free end portion of the shaft 78 and bears at one end against the 130

mid-portion of the pawl plate to hold the same against a collar or hub extension 88 upon the adjacent face of the wheel 77, and at its other end bears against a nut or collar or other form of abutment 89 fixed upon the said end of the shaft. This spring of course serves to suitably yieldably resist canting movement of the pawl plate upon the shaft. One end of the plate 85 is provided with a tooth or shoulder 90, and the opposite end is provided with a finger indicated by the numeral 91. The tooth 90 projects opposite the path of movement of a number of abutment elements 92 upon the face of the wheel 77 and each of which elements preferably comprises a suitable length of wire secured at its ends as at 93 to the said face of the wheel and for the greater portion of its length inclined outwardly at an angle from the plane of said wheel face and terminating at its more remote portion in an inwardly turned portion forming an abrupt shoulder 94. Other abutment elements 95 of similar formation are provided upon the face of the said wheel 77 preferably at substantially diametrically opposite points and exteriorly of the circular series of elements 92 and have their shoulders, which are indicated by the numeral 96, presented in a direction opposite to that in which the shoulders 94 are presented. The numeral 97 indicates in general a latch comprising a tubular member 98 pivotally connected at one end as at 99 to the detent bar 51 above the fulcrum 52. The opposite end portion of the member 98 is slidably fitted through a bracket 100 upon the inner face of the front wall of the casing. The numeral 101 indicates a tubular latch tooth which is slidably fitted into the last mentioned end of the tubular member or shank 98, and the said member 98 is formed with a slot 102, and the tooth 101 with a slot 103 in alignment with said slot 102, the end of the finger 91 being projected through the slots 102 and 103 and into the tooth 101. The slot 102 is of a length but slightly greater than the width of the finger 91 so that the finger may fulcrum in said slot and will be acted against by the member 98 in its shifting movement when the detent 50 is actuated. However the slot 103 is of a length greater than the width of the finger 91 and therefore the tooth 101 may have inward sliding movement in the shank 98 independent of the movement of the shank. Such movement of the tooth is yieldably resisted by a spring 104 arranged within the shank 98 and bearing at one end against a cross pin or other suitable abutment 105 and at its other end against a similar abutment 106 at the inner end of the tooth 101. The outer end of the tooth 101 is preferably beveled or cut at an angle as indicated by

the numeral 107 so as to adapt it to ride against the inclined portions of the abutment elements 95 or more specifically to permit these abutment elements to ride past the tooth as the wheel 77 is rotated.

When the detent 50 is in the normal position illustrated in full lines in Figure 2 of the drawings, the shank 98 of the latch 97 will be at the limit of its movement in the direction of the wheel 77, and the tooth 101 of said latch will engage behind the shoulder 96 of one of the abutment elements 95 thus inhibiting rotation of the wheel 77 to unwind the flexible connection 75 and preventing unauthorized use of the sledge 73. However after the introduction of a coin into the coin throat 66 and actuation of the detent to move it to the dotted line position shown in said Figure 2, the latch 97 will be drawn away from the wheel 77 and the end of its tooth 101 will be moved out of engagement with the shoulder of the said abutment member 95. This releases the wheel 77 for rotation in a direction to permit unwinding of the connection 75. This movement of the latch 97 will effect a canting of the latch plate 85 bringing its tooth 90 into the path of movement of the abutment elements 92, and as the wheel 77 is rotated through the unwinding pull exerted upon the element 75, the said elements 92 will successively ride past the tooth 90 and the tooth 90 will be urged by the spring 87 to engage successively behind the shoulders 94 of the said elements 92. Thus when a sufficient length of the cable or other connection 75 has been unwound from the wheel to permit of free use of the sledge, the tooth 90 will be engaged behind one of the shoulders 94 and the wheel 77 will be restrained from backward rotation under the influence of the spring 82. As soon however as a blow is struck upon the anvil member and the detent 50 returns to its normal position, the tooth 90 will be moved out of the path of the members 92 and the wheel 77 may then rotate, under the influence of the spring 82, in a backward direction to wind up the surplus length of the connection 75, the abutment elements 95 successively riding past the beveled end of the tooth 101 and in so doing forcing this tooth inwardly against the tension of the spring 104.

If desired a hook or similar latch device 108 may be mounted upon the inner side of the front wall 2 of the casing in position for engagement with a keeper 109 upon the detent 50 so as to hold the detent in the inactive or dotted line position in Figure 2 for an indefinite period of time, and by making use of this means, the proprietor of the machine may render the anvil member responsive to blows which may be suc-

sively struck without attention to the actuation or adjustment of the detent in the manner previously explained.

Having thus described the invention, 5 what is claimed as new is:

1. In a striking machine, an anvil member, an indicator shaft, a volute wing upon said shaft, indicator mechanism actuated through rotation of the shaft, and a rider 10 actuated through movement of the anvil member upon the application of force thereto to move in the path of the active surface of the cam and effect rotation of the said shaft.
- 15 2. In a striking machine, an anvil member, a member positioned to be acted upon and impelled by the anvil member upon the application of force to the latter, a rotatable shaft, indicator mechanism actuated 20 through rotation of the shaft, and a member fixed upon and rotatable with the shaft and having a volute wing in the path of movement of said member.
- 25 3. In a striking machine, an anvil block, an anvil member fulcrumed upon the block and having an impact portion designed to rest upon a surface of the block when the anvil member is in position non-responsive to force applied thereto, means normally 30 held in coactive relation to the anvil member to retain the same in such position, and means whereby the retaining means may be rendered inactive.
- 35 4. In a striking machine, an anvil member, indicator means actuated through movement of the anvil member upon application of force thereto, a sledge retained in proximity to the anvil member and constituting means whereby a blow may be struck 40 upon the anvil member, a flexible element connected with the sledge, means upon which the said element is wound, and means normally restraining the last mentioned means from actuation to unwind the said 45 element and actuatable to be rendered inactive.
- 50 5. In a striking machine, an anvil member, indicator means actuated through movement of the anvil member upon application of force thereto, a sledge retained in proximity to the anvil member and constituting means whereby a blow may be struck 55 upon the anvil member, a flexible element connected with the sledge, means upon which the said element is wound, means normally restraining the last mentioned means from actuation to unwind the said element and actuatable to be rendered inactive, and means influencing actuation of 60 the said winding means to rewind the flexible element thereon after it has been unwound.
- 65 6. In a striking machine, an anvil member, indicator means actuated through movement of the anvil member upon appli- 70 cation of force thereto, a sledge retained in proximity to the anvil member and constituting means whereby a blow may be struck upon the anvil member, a flexible element connected with the sledge, means upon which the said element is wound, means normally restraining the last mentioned means from actuation to unwind the said element and actuatable to be rendered inactive, means influencing the actuation of 75 the said winding means to rewind the flexible element thereon after it has been unwound, and means operable to restrain the winding means from actuation to rewind the said flexible element. 80
- 85 7. In a striking machine, an anvil member, indicator means actuated through movement of the member upon application of force thereto, a rotary winding wheel, means influencing rotation of the wheel in one direction, a flexible element connected with the winding wheel and adapted to be wound thereon when the wheel is rotated in said direction, a sledge to which the said flexible element is connected and constituting means whereby a blow may be struck upon the anvil member, a latch member, an abutment upon the said wheel for coaction with the latch member to restrain the wheel against rotation in a direction to unwind the flexible element, and means operable to render the latch inactive. 90
- 95 8. In a striking machine, an anvil member, indicator means actuated through movement of the member upon application of force thereto, a rotary winding wheel, means influencing rotation of the wheel in one direction, a flexible element connected with the winding wheel and adapted to be wound thereon when the wheel is rotated in said direction, a sledge to which the said flexible element is connected and constituting means whereby a blow may be struck upon the anvil member, a latch member, an abutment upon the said wheel for coaction with the latch member to restrain the wheel against rotation in a direction to unwind the flexible element, and means operable to render the latch inactive. 100
- 105 9. In a striking machine, an anvil member, indicator means actuated through movement of the member upon application of force thereto, a rotary winding wheel, means influencing rotation of the wheel in one direction, a flexible element connected with the winding wheel and adapted to be wound thereon when the wheel is rotated in said direction, a sledge to which the said flexible element is connected and constituting means whereby a blow may be struck upon the anvil member, a latch member, an abutment upon the said wheel for coaction with the latch member to restrain the wheel against rotation in a direction to unwind the flexible element, means operable to render the latch inactive, a second abutment element upon said wheel, and means for coaction therewith to prevent rotation of the wheel under the influence of the said rotating means. 110
- 115 10. In a striking machine, an anvil member, indicator means actuated through movement of the member upon application of force thereto, a rotary winding wheel, means influencing rotation of the wheel in one direction, a flexible element connected with the winding wheel and adapted to be wound thereon when the wheel is rotated in said direction, a sledge to which the said flexible element is connected and constituting means whereby a blow may be struck upon the anvil member, a latch member, an abutment upon the said wheel for coaction with the latch member to restrain the wheel against rotation in a direction to unwind the flexible element, means operable to render the latch inactive, a second abutment element upon said wheel, and means for coaction therewith to prevent rotation of the wheel under the influence of the said rotating means. 120
- 125 11. In a striking machine, an anvil member, indicator means actuated through movement of the member upon application of force thereto, a rotary winding wheel, means influencing rotation of the wheel in one direction, a flexible element connected with the winding wheel and adapted to be wound thereon when the wheel is rotated in said direction, a sledge to which the said flexible element is connected and constituting means whereby a blow may be struck upon the anvil member, a latch member, an abutment upon the said wheel for coaction with the latch member to restrain the wheel against rotation in a direction to unwind the flexible element, means operable to render the latch inactive, a second abutment element upon said wheel, and means for coaction therewith to prevent rotation of the wheel under the influence of the said rotating means. 130

latch member to restrain the wheel against rotation in a direction to unwind the flexible element, means operable to render the latch inactive, a second abutment element upon said wheel, and means for coacting therewith to prevent rotation of the wheel under the influence of the said rotating means, the means coacting with the last mentioned abutment upon the winding wheel being operable to be rendered active upon movement of the latch to inactive position.

10. In a striking machine, an anvil member, indicator means actuated through movement of the anvil member upon the application of force thereto, a shaft, a winding wheel rotatable upon the shaft, a flexible element connected with the wheel to be wound thereon, means influencing rotation 15 of the wheel in a direction to wind the said element thereon, a sledge to which the said flexible element is connected and constituting means whereby a blow may be struck upon the anvil member, a pawl member 20 freely fulcrumed upon the shaft, means yieldably resisting movement of the pawl member, a shiftable latch, means for shifting the latch, and abutment elements upon 25 the wheel for coaction with the latch and with the pawl member, the pawl member being movable in consonance with the movement of the latch whereby when the latch

is engaged the pawl member will be disengaged and vice versa.

11. In a striking machine, an anvil member, a shaft, means actuated through movement of the anvil member upon application of force thereto to impart rotary motion to the shaft, and independent and distinguishable audible signals actuated at different 35 periods in the rotation of the shaft.

12. In a striking machine, an anvil member, a shaft, means actuated through movement of the anvil member upon application of force thereto to impart rotary motion to the shaft, independent and distinguishable 40 audible signals, means for sounding said signals, and operative connection between each of the last mentioned means and the shaft for actuating said means at different 45 periods in the rotation of the shaft.

13. In a striking machine, an anvil member, indicator means actuated through movement of the anvil member upon the application of force thereto and including a rotatable shaft, and friction means operable to automatically arrest the rotation of the shaft substantially at the moment the same ceases to be rotated through the force applied thereto.

55 In testimony whereof I affix my signature.

CLARENCE L. BARNHART. [L.S.]
